UNITED STATES PATENT OFFICE

2,200,647

CONVERTIBLE CHAISE COT-BED

Henry Vanderploeg, Chicago, Ill., assignor to
 Haggard and Marcusson Company, Chicago,
 Ill., a corporation of Illinois

Application August 11, 1939, Serial No. 289,564

4 Claims. (Cl. 155—45)

My invention relates to furniture and particularly to a reclining seat that may readily be convertible into a full length couch or cot-bed.

I am aware that, broadly stated, the foregoing is not novel. However, I have devised a construction in which the chaise is properly designed for the utmost comfort; that is, in which the back is inclined, in which the seat is downwardly and backwardly inclined and in which the leg section is downwardly and forwardly inclined. In order to convert this design into a cot-bed in which the sections lie in a horizontal plane, an ingenious system of links is employed that operate automatically to accomplish the desired result by the simple action of lowering the back section of the chaise.

The invention will be more readily understood by reference to the accompanying drawing; in which,

Fig. 1 is a side elevation of a frame of a chaise arranged in accordance with my invention; and,

Fig. 2 is a side elevation of the frame when in extended horizontal position to provide a cot-bed.

For simplicity I have omitted the upholstery or padding that may be supplied to the frame. Furthermore, for simplicity in nomenclature I have, in the specification and claims, referred to the supports and links in the singular, as the structure appears in side elevation. It will be understood, however, that such parts are duplicated on the opposite side of the structure.

The illustrated frame structure provides a back section 10, a seat section 11 and a leg section 12. The back section is provided with a headed pin 13 and a side arm 14 which is pivotally connected to the seat at 15 and has a bayonet slot 16 adapted to engage with the pin 13 to hold the back in sitting relation.

The respective sections are joined by hinges 17—18. The structure is supported by legs 19—20, the latter terminating in a wheel 21, the legs being joined by a link 22. The back section is joined to the support 20 by a curved link 23, the curve being provided in order to prevent interference with the axle bearing 24 for the axle 21. The leg section is connected by a link 25 to the support 19. The back section is provided with its own supporting leg 26 which is adapted to be folded into the back section when the frame is in sitting relation, as shown in Fig. 1.

With the parts in the position of Fig. 1, it will be noted that the supports 19—20 diverge, the support 19 being longer than the support 20. As the back is lowered, the links 23, 22 act on the supports to move the support 20 into a more

vertical position, thus raising the rear of the seat section and to move the support 20 into a more inclined position, thus lowering the forward end of the seat section. This movement of the support 19 acts through the link 25 to raise the leg section 12. By removing the third support 26 from the frame, the outer end of the back section is suitably supported, the length of the leg 26 or the curvature of the back section, if any, being used to slightly elevate the upper end of 10 the cot-bed if desired.

It will be understood that the various terms used in the accompanying claims, such as links, legs, etc., are not intended as limitations to specific elements of such character, but that other elements having the functions of such parts are contemplated as well.

The construction will be found to be economical to manufacture and simple to operate and modifications within the scope of the appended 20 claims may be made without departure from the spirit of my invention.

I claim:

1. A seating and sleeping device comprising in combination a back section, a seat section and 25 a leg section, respective sections being joined by hinges, supporting members pivotally connected to the opposite ends of the seat section, the members at the respective ends diverging from each other when the structure is in seating relation, a link connecting the supporting members, a link connecting the back to the adjacent supporting member, a link connecting the leg section to the adjacent supporting member and means for locking the back in seating relation, 30 the arrangement being such that upon lowering the back the adjacent supporting member is moved toward a vertical position to raise the rear of the seat section and the forward supporting member is moved to a more inclined 40 position, thus raising the leg section through the connecting link and lowering the forward end of the seat section.

2. A seating and sleeping device comprising, in combination, a back section, a seat section and 45 a leg section, the respective sections being joined by hinges, supporting members pivotally connected to the opposite ends of the seat section, the members at the respective ends diverging from each other when the structure is in seating 50 relation, a link connecting the supporting members, a link connecting the back to the adjacent supporting members, a link connecting the leg section to the adjacent supporting member, and arms having an interlocking engagement with 55

- the back section when the parts are in seating relation, the arrangement being such that upon lowering the back the adjacent supporting member is moved toward a vertical position to raise the rear of the seat section, and the forward supporting member is moved to a more inclined position, thus raising the leg section through the connecting link and lowering the forward end of the seat section.
3. A seating and sleeping device comprising, in combination, a back section, a seat section and a leg section, the respective sections being joined by hinges, supporting members pivotally connected to the opposite ends of the seat section, the rear supporting member terminating in a wheel, the members at the respective ends diverging from each other when the structure is in seating relation, a link connecting the supporting members, a link connecting the back to the adjacent supporting member, a link connecting the leg section to the adjacent supporting member, and means for locking the back in seating relation, the arrangement being such that upon lowering the back the adjacent supporting member is moved toward a vertical position to raise the rear of the seat section and the forward supporting member is moved to a more inclined position, thus raising the leg section through the

connecting link and lowering the forward end of the seat section.

4. A seating and sleeping device comprising, in combination, a back section, a seat section and a leg section, the respective sections being joined by hinges, supporting members pivotally connected to the opposite ends of the seat section, the members at the respective ends diverging from each other when the structure is in seating relation, a link connecting the supporting members, a link connecting the back to the adjacent supporting member, a link connecting the leg section to the adjacent supporting member, means for locking the back in seating relation, the arrangement being such that upon lowering the back the adjacent supporting member is moved toward a vertical position to raise the rear of the seat section and the forward supporting member is moved to a more inclined position, thus raising the leg section through the connecting link and lowering the forward end of the seat section, and a third supporting member for the back section when in sleeping position, said third supporting member being adapted to be folded into the back section when the parts are in seating position.

HENRY VANDERPLOEG.
